UNITED STATES PATENT OFFICE.

JONAS NORTHROP, OF HOPE DALE, MASSACHUSETTS, ASSIGNOR TO DRAPER COMPANY, OF HOPE DALE, MASSACHUSETTS, A CORPORATION OF MAINE.

AUTOMATIC FILLING-REPLENISHING LOOM.

SPECIFICATION forming part of Letters Patent No. 718,576, dated January 13, 1903.

Application filed February 3, 1902. Serial No. 92,424. (No model.)

To all whom it may concern:

Be it known that I, JONAS NORTHROP, a subject of the King of Great Britain, and a resident of Hopedale, county of Worcester, State 5 of Massachusetts, have invented an Improvement in Automatic Filling - Replenishing Looms, of which the following description, in connection with the accompanying drawings, is a specification, like characters on the drawings representing like parts.

This invention relates more particularly to "automatic" looms wherein upon a change in the condition of the filling, such as breakage thereof or predetermined exhaustion of 15 the supply in the shuttle, the latter is provided with a fresh supply of filling by suitable replenishing mechanism automatically actuated. Such looms require means for effecting automatically such coöperation of the 20 fresh filling-thread and the shuttle as will enable the thread to be properly delivered from the shuttle as the same is shot back and forth through the shed, such means being comprehensively termed "automatic self-threading means." Means for performing 25 such function and carried by the shuttle are in very extended use and operate successfully, the operation, however, being dependent largely, if not wholly, upon the position 30 of the filling-thread between the filling-supply in the shuttle and the replenishing mechanism when the shuttle makes its first shot after replenishment, and this shot and the following return-shot are necessary to effect 35 the complete threading of the shuttle. If the filling-thread is not in the proper position on the first shot, the second shot cannot effect the threading of the shuttle, a mistread resulting, with filling breakage, and a new filling-supply must be inserted in the shuttle. 40 This causes loss of picks, and provision must be made for arresting take-up and letting back more or less according to the number of picks lost to prevent thin places in the cloth 45 and the product of the loom is reduced.

In another application, Serial No. 92,423, filed by me and pending concurrently here-with, I have shown novel means for positively insuring the proper delivery of the filling 50 from the shuttle after filling replenishment, the coöperation of the filling-thread and the

delivery means being effected positively and surely at the instant of replenishment, the thread being so confined as to draw off substantially in axial alinement with the filling-supply, and in such application the subsequent introduction of the filling-thread into the delivery eye of the shuttle is through the movement of the latter then automatically accomplished. That invention absolutely prevents mistreads, and the delivery of the filling is not at all dependent upon the complete so-called "threading" of the shuttle.

My present invention also has for its object the production of means for preventing 65 mistreads and for positively and surely effecting deliverable coöperation of the filling-thread and the shuttle at the time of replenishment; but by the construction forming the subject of this application I "completely" 70 thread the shuttle while it is at rest and practically simultaneously with filling-replenishment, the term "threading" being here used in its usual sense as indicating the insertion of the filling-thread in the delivery-eye of the 75 shuttle, preferably located in its side.

The various novel features of my invention will be hereinafter described, and particularly pointed out in the following claims.

Figure 1 is a front elevation of a portion of 80 a loom equipped with automatic filling-replenishing mechanism of the type shown in United States Patent No. 529,940 and with one embodiment of my present invention applied thereto. Fig. 2 is a part-sectional view 85 thereof on the irregular line 2 2, Fig. 1, locking toward the left, the parts being shown in normal position. Fig. 3 is a similar view of a portion only of the mechanism shown in Fig. 2, but with such parts in the position assumed at the instant the fresh supply of filling has been inserted in the shuttle, the fresh filling-thread having been brought into the delivery-eye of the shuttle. Fig. 4 is a top or plan view of the replenishing end of the lay 90 with the shuttle-box thereon and the shuttle boxed, showing in plan the means for effecting the threading of the shuttle before the latter is picked. Fig. 5 is an inner side elevation of the opener for the thread-retaining 95 lid on the shuttle and the thread-inserter, to be hereinafter described. Fig. 6 is an en-

larged top or plan view of the delivery end of the shuttle with the threading means thereon. Fig. 7 is a side elevation thereof, showing the delivery-eye of the shuttle. Fig. 8 is a transverse section on the line 8 8, Fig. 6, looking toward the right. Fig. 9 is a similar section on the line 9 9, Fig. 6. Fig. 10 is a similar view taken through the retaining-lid on the line 10 10, Fig. 6. Fig. 11 is a like view but showing the lid raised to permit insertion of the filling-thread into the delivery-eye. Fig. 12 is a side elevation of the threading means detached from the shuttle viewed from the delivery side. Fig. 13 is an opposite side elevation of said means; and Fig. 14 is a plan view of said means and the retaining-lid, the latter having been moved away to show more clearly the other portion of the thread-delivering means, which is mounted on the shuttle and on which the lid is movably mounted.

Referring to Figs. 1 to 3, the loom-frame A, lay A³, having the bottom of one of its shuttle-boxes, as B^X, slotted to permit passage therethrough of an ejected filling-carrier, the bunter C² on the lay, and the breast-beam A¹⁰ are and may be of usual or well-known construction. The filling-replenishing mechanism and the means for intermittently rotating the filling-feeder F, forming a part thereof, are and may be substantially as in United States Patent No. 664,790, dated December 25, 1900. The filling-carriers or supplies b of filling are removed one by one from the feeder by the transfferer f', mounted to rock on a stud f, secured to the stand A⁷, a downturned tip-engaging device 22 being secured to the end of a lateral arm 21, secured to the transfferer. As in said Patent No. 664,790, a rock-shaft d' is held in normal position by a spring d³, attached at one end to a rocker-arm d^X, which controls the movement of a swinging shuttle-feeler y^X, having a branch y². This branch, acting against a lug m¹⁴ on the carrier m¹³ of the notched dog m¹⁵, holds the latter out of the path of the bunter C², as in Figs. 1 and 2, the carrier m¹³ being secured to a rocker-stud m¹², mounted in the depending end f³ of the transfferer, a spring m^X, Fig. 1, tending always to turn the rocker-stud, and thereby move the dog into the bunter-path. When the rock-shaft d' is turned in the direction of arrow 15, Fig. 2, as it will be upon such a change in the condition of the filling as hereinbefore referred to, the dog m¹⁵ will be engaged by the bunter C² on the beat-up of the lay and the replenishing mechanism will be operated in well-known manner, the shuttle being properly boxed. In Fig. 3 the parts are in the position assumed when the fresh filling-carrier is in the shuttle S, provided with suitable holding means, as jaws s', Fig. 4, to engage and hold the head of the filling-carrier.

Referring to Fig. 1, a disk b², having a holding-stud b³, is secured to the outer end of the feeder F to rotate therewith, the filling end t being led from the tip of each filling-supply

in the feeder, over the edge of disk b², and then to the stud b³ to hold such end when replenishment of filling takes place. For a reason 70 to be referred to, however, the filling end is not led in a direct line from the feeder to the disk b²; but, as shown in Fig. 1, it is slanted or so set that its point of engagement with the disk b² will be in advance angularly of the 75 filling-supply from which it is led, the feeder rotating in direction of arrow 16, Fig. 2. The front wall b^X of the shuttle-box B^X is made somewhat shorter than usual at its outer end to expose the side delivery-eye s² of the shuttle when the latter is properly boxed, and the front of the lay is notched, as at a³, Figs. 1 and 4, at the outer side of an upturned actuator a⁴, fixed on the lay, for purposes to be described. The hub f² of the transfferer is 80 partly embraced by the segmental end 25 of a bracket 26, the shape of which is best shown in Fig. 1, extended laterally toward the outer end of the fixed stud f, which is herein made longer than usual, the outer end of the bracket 90 forming a segmental seat 27 for the circular hub 28 of an arm 29, said hub being mounted to rock on the stud f and adjustably secured to the seat 27 by a set-screw 30, passed through a slot 31 in said seat. A set-screw 32, passed 95 through a slot 33 in the inner end 25 of the bracket into the hub f², adjustably secures the bracket to said hub, and by such connection the arm 29 will rock in unison with the transfferer and about the same fulcrum f. 100 The arm 29 is located opposite the outer end of the shuttle-box B^X, as best shown in Fig. 4, and its top 34 is widened to form a firm support for a lid-opener, shown as a piece of stiff metal 35, having its rear end reduced and 105 downturned, as at 36, for a purpose to be described, said lid-opener being adjustably secured on the arm 29 by a suitable bolt 37, passed through longitudinal and overlapping slots 38 39 in the opener and top of the arm 110 29, respectively. The said arm has also a depending ear 40, (see Fig. 5,) provided on its rear edge with a notch 41 to receive the lateral stop-lug 42 on a rocker 43, shown as fulcrumed at 44 on the ear 40 and having a depending laterally-extended lug 45, movable 115 into the path of the actuator a⁴ when a change of filling is effected, as will be described. The rocker 43 has adjustably secured to it, as by a bolt 46, the thread-inserter, a casting of 120 peculiar shape and best shown in Figs. 1, 2, and 5. The body 47 of the inserter is longitudinally slotted at 48 to receive the bolt 46, and the rear end of the body is bent to form a gooseneck 49, the downturned bill 50 of the 125 gooseneck being also bent outwardly, as in Figs. 1 and 4. The downturned hook thus formed by the gooseneck and its bill is adapted to hook over the filling end between the outer end of the filling-feeder F and the disk 130 b² as the corresponding filling-carrier is transferred from the feeder to the shuttle, and after the transfferer f' has been depressed by coöperation of the bunter C² and dog m¹⁵ the

actuator a^4 will by the completion of the forward movement of the lay engage the offset lug 45 and rock the gooseneck about the center 44 into the position shown in Fig. 3, a 5 spring 51, attached to the lid-opener and thread inserter, normally maintaining the gooseneck in the position shown in Figs. 2 and 5, with the stop-lug 42 in the notch 41. It will be remembered, however, that the 10 movement of the gooseneck will at first be in unison with the movement of the transerrer f' and about a common fulcrum f during the exceedingly short portion of time which elapses between the engagement of the bunter C^2 and the notched dog and the subsequent engagement of the actuator a^4 with the lug 45, so that the complete movement of the gooseneck from normal position to the position shown in Fig. 3 is compound. The first 15 part of its movement brings the gooseneck into engagement with the filling end t , and the final part of such movement positively inserts the filling end in the thread-passage and delivery-eye of the shuttle, such passage and eye having been previously opened by or 20 through the action of the downturned end 36 of the lid-opener 35, as will be described.

In Fig. 4 the lid-opener is shown as having 25 opened the lid of the threading means on the shuttle, and the filling end or thread t is shown as having been inserted by the gooseneck into the thread-passage and delivery-eye, the notch a^3 in the front of the lay permitting the final movement of the thread-inserter. As soon as 30 the pressure of the actuator a^4 upon the lug 45 is removed, as by the backward movement of the lay, the spring 51 instantly operates to swing the thread-inserter upward on its fulcrum 44 into the relative position shown in 35 Fig. 5, and thereafter as the transerrer f' resumes its normal position the lid-opener and thread-inserter will be moved bodily therewith back into their normal positions (shown in Fig. 2) and entirely out of the way 40 of the filling-thread as the threaded shuttle is shot from the shuttle-box B^x . In order that the thread-inserter may engage the filling-thread, as has been described, it is necessary to set the filling end ahead of the disk b^2 , 45 as shown in Fig. 1 and hereinbefore referred to, as otherwise the thread-inserter could not catch the thread to insert it upon movement of the inserter into operative position.

The construction of the threading or thread-delivering means on the shuttle will now be 50 described, having reference more particularly to Figs. 6 to 14, inclusive.

The body of the shuttle S is provided with a longitudinal opening s^3 , suitably shaped to 55 receive the filling supply or carrier b , the holding device s' being located at one end of said opening, and at the opposite end the shuttle-body is cut out to receive the threading or delivering device, (shown separately in Figs. 6 60 and 12 and 13 as viewed from opposite sides.) In its side the shuttle is cut away to leave a substantially horizontal shelf s^4 , and presenting

an upright edge s^5 at its rear, while the upright and beveled front wall has preferably secured to it a friction-pad s^6 , of felt or other suitable tension-producing material, the friction-pad and upright edge s^5 forming, with the shelf s^4 , a reentrant opening in the side of the shuttle, constituting a species of vestibule, as it were, for the delivery-eye s^2 . The 75 threading-block is preferably made as a casting and comprises a base 60, having a depending threaded stud 61 to pass through a hole in the bottom of the shuttle and to receive a retaining-nut 62, which enters the counter-sunk end of the hole s^7 in the shuttle, as shown in Fig. 10. An additional securing device comprises a transverse bolt 63, passed through the shuttle from side to side and through a hole 64 in the base 60. 80

Referring to Fig. 14, the base has a diagonal thread passage or groove 65, which, as shown in Fig. 6, has its inner end substantially opposite and in front of the tip of the filling-carrier, in axial alignment therewith, 85 while its outer end s^8 constitutes the lower part of the delivery-eye and opens out upon the shelf s^4 . At its front end the base has an upturned transverse ear 66 and at its rear end a second ear 67, said ears supporting a pin 68, on which is fulcrumed the lid to be described. The ear 66 is upwardly and forwardly extended, as at 69, presenting a stop-shoulder 70, while the ear 67 is upwardly extended and convexed, as at 71, to 90 form one side of a flaring mouth for the passage 65, the opposite side of the mouth or entrance being formed by the inner end of the outwardly beveled or flared front wall 72 of the thread-passage, said front wall having a recess or pocket 73 therein. The front upright edge of the said wall is rearwardly beveled, as at 74, and inside such beveled edge the wall has an upright recess 75, the lower end of which is just above and immediately in front of the eye s^2 , Fig. 14. A movable lid member 76 has a longitudinal rib 77 on its top along its rear edge and two depending ears 78 79 on its under side, (see Fig. 13,) the fulcrum-pin 68 passing through 95 the ears to thereby pivotally support the member 76, the ears thereof entering between the upturned ears 66 67 on the base. The edge of the member 76 is transversely convexed, and the ear 78 is extended forward, as at 80, to constitute the lid proper for the eye s^2 , said lid being adapted to enter the groove 75 under normal conditions (see Fig. 10) and contact with the bottom thereof to thus positively close the open top or entrance to the said eye, a spring s^{12} , Figs. 10 and 13, acting upon the lid member 76 back of its fulcrum to retain it in the position shown. The lid 80 is grooved on its rear face, as at 81, to assist in guiding the filling-thread into the open eye when the lid is lifted, the front face being also grooved, as at 82, to guide the filling should it be delivered over the top of the shuttle. Near the 100

lid 80 the member 76 is cut away to present a shoulder 83, which butts against the upright shoulder 70 when the lid is in normal position to thereby close the space between the lid and the convex front face of the extension 69 and prevent the thread from being caught. At its rear end the member 76 is shaped to form a downturned guard 84, which normally spans the inner end of the passage 65 and enters the recess 73 in its front wall, the rear edge of the guard being concaved, as at 85.

Referring to Fig. 6, it will be seen that when the parts are in normal condition the passage 65 is covered by the lid member 76 from the rear edge of the guard 84 to the delivery-eye s^2 , the latter being shut by the lid 80, as described, and if the thread has been inserted in the eye while open it cannot thereafter escape and is positively retained therein. The convex upper and front surfaces of the guard 84 and member 76 act to direct the thread thereover and down into the thread-passage back of the eye, and when the thread is drawn beneath the point of the guard the latter prevents it from throwing or twisting out of the entrance end of the passage. A transverse slot 86 in the rear end of the base 60 receives a piece 87 of felt or other suitable friction material to act upon the thread as it is drawn through the passage to the delivery-eye.

Referring to Figs. 7 and 12, the front wall of the passage 65 has a depending prong 88, which enters the shuttle-wood and bears against the upright rear wall s^5 of the vestibule to present a smooth surface for the thread to pass over during its delivery when the shuttle is thrown from left to right. So long as the loom continues to run under proper operative conditions the parts mounted on the shuttle will remain in the relative positions shown in Figs. 6 to 10, but when filling replenishing is necessary a rapid change is effected. When the transerrer f' is moved to insert a fresh supply of filling in the shuttle, the lid-opener 35 is moved until its tip 36 engages the top of the member 76 against the rib 77 behind the fulcrum, and as the filling-supply enters the shuttle the lid-opener will tilt the member 76 into the position shown in Fig. 11 against the action of the spring s^{12} to thereby open the delivery-eye s^2 of the shuttle. At the same time the transerrer movement has brought the thread-inserter into operative position, so that the gooseneck 49 hooks over the fresh filling-thread just outside the shuttle and near the delivery-eye. Then as the lay completes its forward movement the actuator a^4 hits the lug 45 and rocks the thread-inserter on the center 44 into the position shown in Fig. 3, thereby drawing the thread down over the convex front of the member 76 and the front edge of the lid 80 between the parts 69 and 74 and into the then open eye. As the lay swings back thereafter the lid closes down onto the open top of the

eye, absolutely preventing withdrawal of the thread, and the thread is ready for instant delivery before the shuttle has started from the replenishing shuttle-box—i. e., before it has been picked. When the thread is inserted in the eye, as described, it may or may not at the same time shed over the guard 84 and into the thread-passage 65; but if it does not do so immediately the pull of the thread will soon cause it to slide down between the convexed front edge of the member 76 and the flared face of the wall 72 into the passage and under the guard, the point of which enters but does not touch the bottom of the recess 73, as shown in Fig. 9. So far as effective operation is concerned the shuttle is completely threaded for delivery of the filling before the shuttle leaves the shuttle-box and at the instant of filling replenishing. The bottom of the passage 65, leading to the delivery-eye, is practically in a horizontal plane intersecting the center of the filling-carrier, so that the thread is drawn off the latter in a line very closely coinciding with the longitudinal axis of the filling-carrier, so that there is no undue strain on the thread due to oblique pull on the first pick after replenishment. After the thread is inserted in the passage 65 and the eye and confined therein its path is easy and free.

The end of the supply of filling from which the thread draws off during weaving is termed the "delivery" end of the filling-supply and is so designated in some of the following claims.

My invention is not restricted to the precise construction and arrangement shown and described, as the same may be modified or varied in different particulars without departing from the spirit and scope of my invention.

Having fully described my invention, what I claim as new, and desire to secure by Letters Patent, is—

1. In a loom provided with automatic filling-replenishing mechanism, a shuttle adapted to contain a supply of filling and provided with a thread-receiving passage terminating in a delivery-eye, and a movable lid for said passage, combined with a lid-opener, and a thread-inserter, operative upon filling replenishing to move the lid and effect the insertion of the fresh filling-thread into the thread-passage.

2. In a loom provided with automatic filling-replenishing mechanism, a shuttle adapted to contain a supply of filling and provided with a delivery-eye, and a movable lid for and normally closing the entrance to said eye, combined with a lid-opener and thread-inserter means, operative upon filling replenishing to retract the lid and positively insert the fresh filling-thread in the delivery-eye.

3. In a loom provided with automatic filling-replenishing mechanism, a shuttle adapted to contain a supply of filling and provided with a delivery-eye having a flaring entrance, and a normally closed lid to complete the eye,

combined with a lid-opener and thread-inserting means operative successively upon actuation of the filling-replenishing mechanism, to first move the lid to open the eye-entrance, and then insert the fresh filling-thread into the open eye through the flaring entrance thereof.

4. In a loom provided with automatic filling-replenishing mechanism, a shuttle adapted to contain a supply of filling and provided with a side delivery-eye, and a movable lid for and normally closing the entrance to said eye, combined with a lid-opener operative by or through actuation of the replenishing mechanism, to lift the lid, means to insert the fresh filling-thread into the eye when the lid is lifted, and an independent actuator for and to operate said means subsequent to the opening of the eye.

5. In a loom provided with automatic filling-replenishing mechanism, a shuttle adapted to contain a supply of filling and provided with a side delivery-eye, a thread-passage leading from the interior of the shuttle to and terminating in said eye, and a normally closed lid for the delivery-eye and adapted to overhang said passage, combined with means to lift the lid to open the eye and clear the passage upon filling replenishing, and independent means to effect the insertion of the fresh filling-thread in said passage and the eye while open.

6. In a loom provided with automatic filling-replenishing mechanism, a shuttle adapted to contain a supply of filling and provided with a side delivery-eye, a thread-passage leading diagonally from in front of the tip end of the filling-supply to the delivery-eye of the shuttle, and a movable lid to normally close the eye, combined with means independent of the shuttle to positively open the lid and insert the fresh filling-thread in the passage and into the open eye upon actuation of the replenishing mechanism.

7. In a loom provided with automatic filling-replenishing mechanism, a shuttle adapted to contain a supply of filling and provided with a side delivery-eye, and a spring-controlled lid forming the top of and normally closing the eye, said lid having a convex thread-directing surface, combined with a device operative to move the lid and open the eye when a fresh supply of filling is inserted in the shuttle, and means to automatically engage the fresh filling-thread and positively insert the same in the delivery-eye while the lid is retracted.

8. In a loom provided with automatic filling-replenishing mechanism, a shuttle adapted to contain a supply of filling and provided with a normally closed delivery-eye, and means mounted independently of the shuttle to automatically open the eye and positively engage and insert therein the fresh filling-thread when a fresh filling-supply is inserted in the shuttle.

9. In a loom provided with automatic fill-

ing-replenishing mechanism, a shuttle adapted to contain a supply of filling and provided with a normally closed delivery-eye, means operated by or through filling replenishing to open the eye, and separate means automatically operated to engage and insert the fresh filling-thread in the eye while open.

10. In a loom provided with automatic filling-replenishing mechanism, a shuttle adapted to contain a supply of filling and provided with a normally closed delivery-eye, and separate and independently-actuated means to successively open the delivery-eye, and positively engage and insert therein the thread of a filling-supply freshly inserted in the shuttle.

11. In a loom provided with automatic filling-replenishing mechanism, a shuttle adapted to contain a supply of filling and provided with a side delivery-eye, and a lid to normally close the top of the eye, combined with a lid-opener operative by actuation of the replenishing mechanism to lift the lid and open the eye when fresh filling is inserted in the shuttle, and means to engage and depress the fresh filling-thread into the open eye, return of the lid to normal position positively closing the eye and maintaining the thread therein, before the shuttle is picked.

12. In a loom provided with automatic filling-replenishing mechanism, a shuttle adapted to contain a supply of filling and provided with a side delivery-eye having a top entrance and flared side walls adjacent thereto, and a lid to normally close the entrance and having a substantially upright guide-groove in its outer face, combined with a lid-opener operative upon actuation of the replenishing mechanism to lift the lid and open the eye, and means to automatically engage and insert into the open eye the fresh filling-thread, the groove in the lid serving to guide the thread upon delivery thereof over the top of the shuttle.

13. In a loom provided with automatic filling-replenishing mechanism, a shuttle adapted to contain a supply of filling and provided with a side delivery-eye and thread-delivering means, comprising a thread-receiving passage leading to the eye, and a movable lid for and to normally close the eye and having at its inner end a depending exteriorly-convex guard to overhang the passage near its inner end, combined with a lid-opener operative upon actuation of the replenishing mechanism to move the lid and open the eye and thread-passage, and means to engage and insert the fresh filling-thread into the open eye and outer end of the passage, the convex surface of the guard directing the thread into the inner end of the passage, the guard thereafter preventing accidental escape of the thread.

14. In a loom provided with automatic filling-replenishing mechanism, the lay, a shuttle-box thereon adjacent said mechanism, an actuator on the lay, and a shuttle adapted to

- contain a supply of filling and provided with a normally closed delivery-eye, combined with means operative upon actuation of the replenishing mechanism to open the delivery-eye, and means, operated by the actuator as the lay beats up, to engage the fresh filling-thread and insert it in the open eye while the shuttle is in the replenishing shuttle-box.
15. In a loom provided with automatic filling-replenishing mechanism, including a transerrer, the lay, a shuttle-box thereon adjacent said mechanism, an actuator on the lay, and a shuttle adapted to contain a supply of filling and provided with a normally closed delivery-eye, combined with means to open the eye, and thread-inserting means, the former means being actuated by operation of the transerrer and the latter means being moved thereby into operative position, the thread-inserting means being thereafter operated by the actuator on the lay, to positively insert the fresh filling-thread into the open delivery-eye of the shuttle while the latter is in the replenishing shuttle-box.
25. 16. In a loom provided with automatic filling-replenishing mechanism, a shuttle adapted to contain a supply of filling and provided with a side delivery-eye, and a movable lid to normally close the eye, combined with a lid-opener actuated by the replenishing mechanism to lift the lid and open the delivery-eye, thread-inserting means movable by operation of said mechanism into operative position to engage the fresh filling-thread, and an actuating device to thereafter automatically effect the operation of said means to positively insert the fresh filling-thread into the delivery-eye while the lid thereof is lifted.
17. A shuttle for automatic filling-replenishing looms, adapted to contain a supply of filling and having a delivery-eye with an open top, a straight thread-passage leading from in front of the delivery end of the filling-supply directly to the delivery-eye, a pivotally-mounted lid for the latter, and means to normally maintain the lid in position to positively close the open top of the eye and partly overhang the thread-passage.
18. A shuttle for automatic filling-replenishing looms, adapted to contain a supply of filling and having a delivery-eye having an open, flaring top entrance, a straight thread-passage leading from in front of the delivery end of the filling-supply to the delivery-eye, the front wall of said passage being beveled, and a spring-controlled, pivotally-mounted lid normally maintained in position to positively close the open top entrance of the eye and partly overhang the thread-passage.
60. 19. A shuttle for automatic filling-replenishing looms, adapted to contain a supply of filling and having a side delivery-eye with an open-top entrance, a straight thread-passage having a flared inner end located in front of the delivery end of the filling-supply and leading diagonally and directly to the delivery-eye, a movable lid for the latter, having a thread-guard for the passage near its inner end, and means to normally maintain the lid in position to positively close the top of the eye and with the thread-guard extended across the thread-passage near its inner end.
20. A shuttle for automatic filling-replenishing looms, adapted to contain a supply of filling and having a delivery-eye with an open top, a thread-passage leading from in front of the delivery end of the filling-supply to the delivery-eye, a pivotally-mounted lid having a depending portion to span the outer end of the passage and positively close the open top of the delivery-eye, an overhanging, downturned guard movable with the lid, to extend across the inner end of the thread-passage, and means to normally depress the lid to close the eye and maintain the guard in operative position.
21. A shuttle for automatic filling-replenishing looms, adapted to contain a supply of filling and having a side delivery-eye with an open top, a diagonal thread-passage leading thereto from in front of the delivery end of the filling-supply and having its front wall beveled and provided with a socket near its inner end, a pivotally-mounted member having an exteriorly-convexed, downturned portion to form a lid for and to close the open top of the eye, a downturned, rearwardly-bent guard at the inner end of said pivoted member, to normally span the thread-passage near its inner end and enter the socket, to prevent the filling-thread from being accidentally thrown out of the passage, and a spring to normally maintain the pivoted member in operative position.
22. In a loom provided with automatic filling-replenishing mechanism, a shuttle adapted to contain a supply of filling and provided with a delivery-eye having a flaring entrance to the top thereof, a thread-passage having its inner end substantially in axial alinement with the filling-supply and leading to the delivery-eye, and a movable lid to normally and positively close the top of the eye, combined with means operative upon filling replenishment to move the lid to open the eye, and means to engage and draw the fresh filling-thread down the flaring entrance into the eye while the latter is open and before the shuttle is picked.
23. In a loom provided with automatic filling-replenishing mechanism, a shuttle adapted to contain a supply of filling and provided with threading means, including a delivery-eye having a top entrance, and a lid to normally close the eye, combined with means operative upon filling replenishment to open the eye and positively insert the fresh filling-thread therein before the shuttle is picked.
24. In a loom provided with automatic filling-replenishing mechanism, a shuttle adapted to contain a supply of filling and provided with a normally closed delivery-eye, a thread-passage leading to the eye and having its bottom substantially in a horizontal plane con-

taining the longitudinal axis of the filling-supply, means operated upon filling replenishing to open the eye, and separate means to automatically engage and insert the fresh 5 filling-thread in the passage and the delivery-eye while the latter is open.

In testimony whereof I have signed my

name to this specification in the presence of two subscribing witnesses.

JONAS NORTHROP.
